JOHN WYNN, JR., OF CANTON, OHIO.

SUCTION-MACHINE.

1,234,598.

Specification of Letters Patent. Patented July 24, 1917.

Application filed January 14, 1915. Serial No. 2,136.

To all whom it may concern:

Be it known that I, JOHN WYNN, Jr., a citizen of the United States, residing at Canton, in the county of Stark and State of Ohio, have invented certain new and useful Improvements in Suction-Machines, of which the following is a specification.

This invention relates to suction machines of the centrifugal type, more particularly to devices of the type commercially termed vacuum cleaners, and has for its primary object to provide a machine of such class, in a manner as hereinafter set forth, with means to facilitate the movement or travel of the air through the machine.

A further object of the invention, is to provide in a machine of the class referred to and in a manner as hereinafter set forth, a suction creating element with a plurality of impellers to facilitate the travel or movement of the air through the machine.

A further object of the invention is to improve generally upon suction machines of the centrifugal type and to further provide a machine which is conveniently accessible for inspection of its parts, readily assembled, simple in construction, strong, durable, having the number of wearing parts reduced to a minimum under such conditions decreasing friction, and comparatively inexpensive to manufacture.

With the foregoing and other objects in view the invention consists of the novel construction, combination and arrangement of parts as hereinafter more specifically described and illustrated in the accompanying drawings wherein is shown an embodiment of the invention, but it is to be understood that changes, variations and modifications can be resorted to which come within the scope of the claims hereunto appended.

In the drawings wherein like reference characters denote corresponding parts throughout the several views:—

45 Figure 1 is a sectional elevation, broken away, of a suction machine in accordance with this invention.

Fig. 2 is an elevation of the lower half of the impeller casing.

50 Fig. 3 is an elevation illustrating the separating diaphragm and the air passage between the impellers, and further showing the vanes for collecting the air from the first impeller and conducting it to the intake of the second impeller.

The drawing shows a suction creating ele-

ment including a pair of impellers, but it is obvious that this number can be increased, the casing being constructed to provide for the additional impeller or impellers. The 60 form illustrated is termed a "two stage" machine as it includes two fans or impellers in series.

Referring to the drawings in detail A denotes a tank or receptacle of the well known type employed in suction machines, termed commercially vacuum cleaning machines now in general use, and mounted thereon, as well as communicating therewith, is the casing of the suction creating element 70 and which is formed of two sections, 1, 2, separated by a diaphragm 3. The section 1 is flanged as at 1^a and said flange rests on the diaphragm 3, the latter being mounted upon the top edge of the side 2^a of the section 2. The side 2^a is thicker than the bottom 2^b of said section 2. The section 1 includes a top 1^b and an open bottom. The section 2 is open at its top. The diaphragm 3 is employed for closing the bottom of the 80 section 1 and top of section 2. The top of the section 1 is depressed and secured thereto is a motor 16 having its shaft 17 extending down through the top 1^b of the section 1.

The diaphragm 3 is secured in position on the section 2, and against section 1, by holdfast devices 4, which extend down through the flange 1^a, through the diaphragm 3 and engage in the side 2^a of the section 2.

The lower section 2, has formed integral 90 with or connected to the bottom 2^b thereof in any suitable manner a series of segmental bars 5, arranged in spaced relation with respect to each other to provide passages constituting outlets 6. The bars 5 are so disposed to form a split annular member or ring and said bars are connected on edge to the bottom 2^b. The annular member or ring forms in connection with the side 2^a of the section 2, an annular air chamber 8 with 100 which the outlets 6 communicate. The outlets 6 are spaced equi-distant so that they form definite ports.

Arranged within the section 2 and surrounded by the annular member or ring is 105 an impeller or fan 7, which is of much less diameter than said member, the latter being of materially less diameter than said section 2. The bars 5 form an air tight space 5^a between the impeller 7 and the air chamber 110 8, and the outlets 6 provide for the discharge of air from the impeller 7 to the chamber 8.

The bottom 2^b of the section 2 has an inlet opening 9 for the passage of air into the impeller 7. The opening 9 establishes communication between the impeller 7 and the 5 receptacle tank A.

The central portion of the diaphragm 3 is offset as at 3^a and fixedly secured to the marginal portion of said diaphragm 3, and arranged below, as well as being spaced from 10 said central offset portion 3^a, is a circular plate 10 which is mounted upon the bars 5. The plate 10 in connection with said central offset portion 3^a provides a passage 13, for the movement or travel of the air from the 15 chamber 8, to an air intake 11, formed at the central part of the offset portion 3^a of the diaphragm 3.

Secured to the lower face of the offset portion 3^a, of the diaphragm 3, is a series of 20 tangentially disposed curved vanes 12, to facilitate the movement or travel of air through the passage 13. The vanes 12 extend from the intake 11 to the outer terminus of the offset portion 3^a.

25 Arranged within the section 1 is an impeller 14 which is of greater diameter than the impeller 7, although if desired both impellers can be of the same diameter. The intake 11 communicates with the impeller 30 14, where the air is acted upon and discharged from the section 1 through the outlet 15 into the atmosphere.

The shaft 17 has attached thereto hubs 18, 19, and to the former is attached the impeller 14 and to the latter the impeller 7. The hubs are attached at one end to the propellers and project to each other. The impeller 7 is operated with its periphery in close proximity to the bars 5 and the impeller 40 14 operated with its periphery in close proximity to the section 1 for a purpose to be hereinafter referred to.

Each of the hubs 18, 19, as before stated is secured at one end to an impeller and the 45 other end has suitable means to attach the unsecured end of the other hub thereto. The hubs when secured to the impellers extend in opposite directions with respect to each other.

50 The general principle of the staged machine is herein shown, consisting of a series of spaced impellers so arranged that the air exhausted from the periphery of one impeller is caused to enter the intake of the next, and so on until the last impeller is passed through, from which the air is exhausted to the atmosphere.

As the air enters the casing it is caused 60 to pass through the first impeller by virtue of centrifugal action, and is then discharged through the ports in the stationary annular member or ring which is placed in close proximity to the periphery of the impeller.

The ports are arranged in such manner and 65 are of such area so as not to interfere with

the velocity of the air as it is discharged from the revolving impeller. The annular member or ring is surrounded by the lower section of the casing of the impellers and together provide the chamber 8 completely 70 encircling the impeller with no opening into the impeller (which it encircles) except the ports before mentioned. The object of this annular chamber is to provide a free and easy space for the air to travel during its 75 movement into the next stage and without the production of eddy currents and back pressure as usually caused by the discharge of the revolving impeller.

A further function of the annular member 80 or ring is to provide a means for eliminating the action of back pressure and eddy currents against the tips of the revolving fan blades. The elimination of this action is accomplished by running the periphery of the 85 impeller at a distance from the annular member or ring not to exceed the width of the opening at the periphery (that is, width of fan blades at periphery or depth of the channels). This keeps the pressure around 90 the periphery of the impeller constant, thus preventing any stray air currents from reacting upon the periphery of the impeller. After the air has been discharged into the annular chamber it is collected by the vanes 95 which are placed in the air space 13 and disposed of at the intake to the next impeller and is conducted through this impeller and again discharged by centrifugal action. The periphery of this second impeller is extended 100 to a point in close proximity to the main casing, to obtain the same effect as is produced by the annular member or ring, as described in connection with the first impeller.

105

The annular member besides preventing back lashing and eddy currents also relieves back pressure of air from the chamber 8, that is to say back pressure of the air discharged from the impeller 7 through the 110 ported annular member into said chamber.

It is well understood that the air after passing from the fan, does not travel as fast as it does while in the fan, nor does it travel as fast as the periphery of the fan, this 115 causes the air at the point of delivery of the fan to form an eddy in a circular motion, similar to a whirl-pool, while still having a motion in the direction of the travel of the fan, the eddy being caused by a revolution 120 of forces and by the same action that produces all whirlpools. This objectionable feature relative to the eddy is overcome by placing the fan in close relation to the casing, as the air within the casing is caused 125 to move as fast as the air which is being discharged from the fan, due to the friction upon that air, thus eliminating any eddy currents that may arise under such conditions preventing back pressure upon the fan, 130

by the same reason, as the air does not strike when forced against the walls of the casing, but continues in a circular motion until exhausted by the fan into the atmosphere.

- 5 The space between the fan periphery and the casing should not be more than the thickness of the fan, because if the discharged air within the casing is greater than the discharge from the fan it would set up 10 the objections which are eliminated by the arranging of the fan with respect to the casing in the manner as illustrated and described.

The bars 5, in connection with the plate 15 10 and bottom of the section 2, provide a chamber for the impeller 7 and the bottom of said impeller chamber has an air in-take, which is the inlet opening 9, and the air enters in the impeller 7 centrally of the bottom 20 thereof. The top of the chamber for the impeller 7 is closed.

The diaphragm 3 in connection with the section 1 forms a chamber for the impeller 14.

25 What I claim is:—

1. The combination in a suction machine of the centrifugal type, of a casing, a peripherally discharging impeller, stationary guide vanes arranged in said casing in the arcs of 30 a circle concentric with the axis of rotation of said impeller to provide an impeller chamber surrounded by an air chamber, an intake for said impeller, said impeller having its periphery spaced from said vanes to 35 provide an uninterrupted annular air space, said vanes being spaced from each other to form radial outlets establishing communication between said space and said air chamber.

40 2. The combination in a suction machine of the centrifugal type, of a casing, a peripherally discharging impeller, stationary guide vanes arranged in said casing in the arcs of a circle concentric with the axis of rotation 45 of said impeller to provide an impeller chamber surrounded by an air chamber, an intake for said impeller, said impeller having its periphery spaced from said vanes to provide an uninterrupted annular air

50 space, said vanes being spaced from each other to form radial outlets establishing communication between said space and said air chamber, a second impeller chamber having an intake, a peripherally discharging 55 impeller operating in said second impeller chamber, and means interposed between said impeller chamber for conducting air from the air chamber to the intake of the second impeller chamber.

60 3. The combination in a suction machine of the centrifugal type, an impeller chamber, an intake therefor, a stationary circular wall arranged within said chamber, an air chamber surrounding said wall, a peripherally discharging impeller arranged within

said impeller chamber and having its periphery spaced from said wall thereby providing an uninterrupted annular air space, and said wall having radially disposed air outlets to establish communication between 70 said air space and said chamber.

4. The combination in a suction machine of the centrifugal type, an impeller chamber, an intake therefor, a stationary circular wall arranged within said chamber, an air chamber surrounding said wall, a peripherally discharging impeller arranged within 75 said impeller chamber and having its periphery spaced from said wall thereby providing an uninterrupted annular air space, 80 said wall having radially disposed air outlets to establish communication between said air space and said chamber, a second impeller chamber, an intake therefor, a peripherally discharging impeller within said second impeller chamber, and means interposed 85 between said impeller chambers for conducting air from the air chamber to the intake of the second impeller chamber.

5. The combination in a suction machine of the centrifugal type, a casing, stationary guide vanes arranged therein in arcs of a circle and providing in said casing an impeller chamber and an air chamber surrounding the impeller chamber, said vanes 90 further providing a circular wall, the combined length of said vanes being less than the total circumference of said wall, an intake for said impeller chamber, a peripherally discharging impeller within said impeller chamber and having its periphery spaced from said wall thereby providing an annular uninterrupted air space, said vanes 95 being spaced from each other to form radial outlets for establishing communication between said space and air chamber, the arcs of the circle in which the vanes are arranged being concentric with the axis of rotation of said impeller.

6. The combination in a suction machine of the centrifugal type, a casing, stationary guide vanes arranged therein in arcs of a circle and providing in said casing an impeller chamber and an air chamber surrounding the impeller chamber, said vanes 110 further providing a circular wall, the combined length of said vanes being less than the total circumference of said wall, an intake for said impeller chamber, a peripherally discharging impeller within said impeller chamber and having its periphery spaced from said wall thereby providing an annular uninterrupted air space, said vanes 115 being spaced from each other to form radial outlets for establishing communication between said space and air chamber, the arcs of the circle in which the vanes are arranged being concentric with the axis of rotation of said impeller.

120 7. The combination in a suction machine of the centrifugal type, a casing, stationary guide vanes arranged therein in arcs of a circle and providing in said casing an impeller chamber and an air chamber surrounding the impeller chamber, said vanes further providing a circular wall, the combined length of said vanes being less than the total circumference of said wall, an intake for said impeller chamber, a peripherally discharging impeller within said impeller chamber and having its periphery spaced from said wall thereby providing an annular uninterrupted air space, said vanes 125 being spaced from each other to form radial outlets for establishing communication between said space and air chamber, the arcs of the circle in which the vanes are arranged being concentric with the axis of rotation of said impeller, a second impeller chamber, an intake therefor, a peripherally discharging 130

5 impeller arranged in said second impeller chamber, and means interposed between said impeller chambers for conducting air from the air chamber to the intake of the second impeller chamber.

7. The combination in a suction machine of the centrifugal type, a casing, stationary guide vanes positioned therein and having a plate mounted thereon thereby providing in said casing an impeller chamber and an air chamber surrounding said impeller chamber, an intake for said impeller chamber, a peripherally discharging impeller arranged within said impeller chamber, and having its periphery spaced from said vanes thereby providing an uninterrupted annular air space, said vanes being arranged in arcs of a circle concentric with the axis of rotation of said impeller, said vanes being spaced from each other to form radial outlets establishing communication between said space and said air chamber.

8. The combination in a suction machine of the centrifugal type, a casing, stationary guide vanes positioned therein and having a plate mounted thereon thereby providing

30 in said casing an impeller chamber and an air chamber surrounding said impeller chamber, an intake for said impeller chamber, a peripherally discharging impeller arranged within said impeller chamber, and having its periphery spaced from said vanes thereby providing an uninterrupted annular air space, said vanes being arranged in arcs of a circle concentric with the axis of rotation of said impeller, said vanes being spaced from each other to form radial outlets establishing communication between said space and said air chamber, a second impeller chamber, an intake therefor, a peripherally discharging impeller positioned in said second impeller chamber, and means interposed between said plate and said second impeller chamber for conducting air from said air chamber to said second impeller chamber.

35 40 45 In testimony whereof I affix my signature in presence of two witnesses.
